DESIGN FOR A PIN

William J. Jorgenson, Los Angeles, Calif.

Application May 27, 1946, Serial No. 130,133

Term of patent 14 years

(Cl. D45—19)

To all whom it may concern:

Be it known that I, William J. Jorgenson, a citizen of the United States, residing at Los Angeles, in the county of Los Angeles and State of California, have invented a new, original, and ornamental Design for Pins, of which the following is a specification, reference being had to the accompanying drawing, forming a part thereof, and in which:

Fig. 1 is a front elevation of the pin showing my new design.

Fig. 2 is a top plan view of the pin shown in Fig. 1.

Fig. 3 is a rear elevational view of the pin.

Fig. 4 is an end elevational view of the pin.

Fig. 5 is a sectional view taken on the line 5—5 of Fig. 1.

I claim:

The ornamental design for a pin, as shown.

WILLIAM J. JORGENSEN.
